UNITED STATES PATENT OFFICE

99,220

DESIGN FOR A DOLL OR SIMILAR ARTICLE

Myles Standish, North Scituate, R. I.

Application January 10, 1936, Serial No. 60,509

Term of patent 14 years

To all whom it may concern:

Be it known that I, Myles Standish, a citizen of the United States of America, residing in North Scituate, county of Providence, State of Rhode Island, have invented a new, original, and ornamental Design for a Doll or Similar Article, of which the following is a specification, reference being had to the accompanying drawing, forming a part thereof.

Fig. 1 is a front elevation of a doll, showing my new design; Fig. 2 is a back elevation; and Fig. 3 is a side elevation, of the same.

I claim:

The ornamental design for a doll or similar article, substantially as shown.

MYLES STANDISH.
